US00D999367S

(12) **United States Design Patent** (10) **Patent No.:** **US D999,367 S**
(45) **Date of Patent:** **** Sep. 19, 2023**

(54) **COMBUSTIBLE LOG TORCH**

(71) Applicants: **David W. Hodsdon**, St. Marys, PA (US); **Michael L. Wahl**, St. Marys, PA (US); **Phillip P. McDonald**, Port Matilda, PA (US)

(72) Inventors: **David W. Hodsdon**, St. Marys, PA (US); **Michael L. Wahl**, St. Marys, PA (US); **Phillip P. McDonald**, Port Matilda, PA (US)

(73) Assignee: **Campfire Innovations LLC**, St. Marys, PA (US)

(**) Term: **15 Years**

(21) Appl. No.: **29/745,194**

(22) Filed: **Aug. 4, 2020**

Related U.S. Application Data

(60) Continuation-in-part of application No. 16/944,448, filed on Jul. 31, 2020, now Pat. No. 11,162,043, which is a division of application No. 15/657,370, filed on Jul. 24, 2017, now Pat. No. 10,731,094.
